BOW TIE

Harry Mann, Laurelton, N. Y.

Application January 23, 1950, Serial No. 7,404

Term of patent 3½ years

(Cl. D3—16)

To all whom it may concern:

Be it known that I, Harry Mann, a citizen of the United States, residing at Laurelton, in the county of Queens and State of New York, have invented a new, original, and ornamental Design for a Bow Tie, of which the following is a specification, a reference being had to the accompanying drawing, forming a part thereof.

Fig. 1 is a front view of a bow tie, showing my new design.

Fig. 2 is a rear view thereof.

Fig. 3 is an end view of the righthand end of Fig. 2.

Fig. 4 is a plan view of the tie before it is folded.

Fig. 5 is a sectional view taken on line 5—5 of Fig. 4.

The essential features of the design reside in the portions shown in solid lines.

I claim:

The ornamental design for a bow tie, substantially as shown and described.

HARRY MANN.
